BOGIE FOR RAIL VEHICLES

Franz Prantl, Wettingen, Switzerland, assignor to
Aktiengesellschaft Brown Boveri & Cie., Baden,
Switzerland, a joint-stock company

Application September 11, 1940, Serial No. 356,402
In Switzerland September 15, 1939

12 Claims. (Cl. 105—190)

It is known with bogies having one driving motor to use this with its axis lying in the direction of travel for the purpose of stiffening the bogie and to provide it with the pivot. If a swing bolster is employed in order to obtain smoother running and higher speeds, this must be located above the motor with the result that the floor of the vehicle must be fairly high above the ground and therefore in an unfavourable position, the various parts of the bogie being subjected to high 10 stresses.

These disadvantages are overcome according to the invention which makes it possible to construct a light and simple bogie with low lying swing bolster and vehicle floor. The invention consists of connecting two motors whose axes are parallel with the driving axles by means of a rigid transverse channel member so as to form a rigid body, inside of which the swing bolster is located.

Two constructional examples of the invention are illustrated in the accompanying drawings where:

Fig. 1 shows a longitudinal section of a vehicle bogie along the line A—A of Fig. 2;

Fig. 2 shows a plan view;

Fig. 3 a cross-section through the transverse channel;

Fig. 4 a front elevational view of the bogie;

Fig. 5 shows a modified construction in longitudinal section.

In the figures the center pin or pivot 1 is located in a transverse beam 2 of the vehicle floor 3 and is connected to the bogie by means of two thrust links 4 and 5 arranged at right angles to each other and provided with ball joints. The link 4 transmits the tensile and compressive forces along the longitudinal axis of the vehicle, while the link 5 transmits the forces in a transverse direction from the bogie to the vehicle. The bogie consists of the two driving motors 6 which are rigidly connected by means of the U-section transverse channel 7 containing the bolster beam 8 and bolster springs 9. The vehicle chassis rests on two rollers 10 on the bolster beam.

According to the constructional example illustrated in Figs. 1-4 the bolster beam 8 consists of a box-sectioned supporting beam provided with a pivot 11 for the attachment of the link 5. The beam 8 is supported at both ends through shackles 12 by the shackle bolts 14 from the leaf springs 9, these latter being secured in the centre by the clamping pieces 15 and fastened to the side walls of the channel piece 7.

One of the motors 6 fixed to the channel 7 is

provided with a pivot 16 to which the longitudinal link 4 is attached; otherwise both motors are the same. The motors 6 are connected to their respective driving axles through a single reduction gearing 17, 18, and universal couplings 19, 20 which are movable in all directions. In the constructional example illustrated the motor 6 which is equipped with a hollow shaft 22, drives through two spring disc couplings 19, 20 the solid shaft 23 which is enclosed by the hollow shaft and carries a pinion 17 located in the gear box 24. The pinion 17 meshes with the gear wheel 18 which is fixed on the driving axle 21. The gear box 24 is supported from the channel by a ball-jointed link 26 and is rigidly fixed to the axle bearing 27 at the opposite end of the driving axle 22 by a casing 28. The entire bogie chassis comprising the motors 6 and channel 7 is supported on four leaf spring bundles 29 by the driving axle bearings which are each suspended by ball-jointed pivot links 30 from the channel 7. In order to prevent lateral movements of the driving axle bearings 27 with respect to the channel 7, the rigid casing 28 which connects the bearings is connected to the motor housing 6 by means of a pivot link 31 located parallel to the driving axle as shown in Fig. 4. The vertical movement of the driving axles 21 relative to the bogie is limited by the stops 32 provided on the motor housings.

With narrow-gauge railways it is advisable to make the body of the driving wheels 25 convex and to locate the inner driving axle bearings inside the hollow space thus provided. Due to the bogie chassis 6, 7 and the carriage framework being supported through the leaf springs 29 by the bearings 27 it is possible to obtain a short wheel base and to concentrate the weight at the fulcrum of the bogie.

The wheel base can be still further reduced if the bolster beam 8 is supported on a number of spiral springs 33 instead of on transverse leaf springs 9, this modified form of the invention being shown in Fig. 5. A pair of strong spiral springs or a number of rubber blocks can be used for this purpose. When it is desired to have larger wheel bases, leaf springs arranged parallel with the longitudinal axis of the vehicle can be used to support the bolster beam 8.

Brake blocks, brake rods and electrical rail brakes can easily be located in the space between the two driving wheels 25.

The ball joints for links 4, 5 and 26 and 30 can be replaced by rubber joints or so-called silent-blocks or combined with these, as indicated in

Fig. 5 for links 4 and 5. Rubber supports can also be employed instead of the leaf springs 29 as is shown in Fig. 5. The beams 34 of the casting connecting the driving axle bearings extend above and below the driving axle in the vertical centre plane and are provided with thick rubber inserts 35 which are enclosed by U-sectioned projections 36, 37. These strong beam like rubber supports are suitable for flexibly transmitting the entire bogie and carriage weight to the driving axles 21. The links 30 (Fig. 1) and links 31 (Fig. 4) can then be omitted.

The bearings for the driving axles can also be constructed as ordinary axle bushings the sliding surfaces of which are located on the bogie chassis 6, 7. Outer bearings can also be used instead of inner bearings.

Further modifications of the constructional examples described above are possible without departing from the spirit of the invention.

The design of the bogie according to the invention is very suitable for light rail vehicles which have to be used on tracks with a small radius of curvature, particularly tramcars; it can, however, be used equally well for trackless road vehicles.

While preferred illustrative embodiments of the invention have been shown and described, it is to be understood that various modifications in the details of construction and mode of operation may be resorted to without departing from the spirit of the invention within the definition of the appended claims.

I claim:

1. A vehicle truck comprising spaced wheeled axles, a transverse channel member disposed intermediate said wheeled axles and having upstanding side walls extending parallel to said axles, a driving motor rigidly secured to the outside of each of said side walls to form a rigid chassis assembly with the shafts of said motors disposed parallel to said axles, means including journal members on said axles for journaling the rigid chassis assembly on said axles, geared driving connections between the respective motor shafts and wheel axles, a bolster housed by said channel member between the side walls thereof, and means for resiliently supporting said bolster in said channel member.

2. A vehicle truck according to claim 1, in which the resilient support for said bolster comprises a plurality of resilient elements carried by said channel member and mounting said bolster channel member therein.

3. A vehicle truck according to claim 1, in which the resilient support for said bolster comprises a plurality of coil spring units mounted within said channel member and mounting said bolster on the upper ends thereof.

4. A vehicle truck according to claim 1, in which the means for journaling the rigid chassis assembly on said axles comprises resilient connecting means supporting said chassis from said journal members on said axles, and link members extending in the direction of travel and pivotally connected at their ends to said journal members and channel member, respectively.

5. A vehicle truck according to claim 1, in which the means for journaling the rigid chassis assembly on said axles comprises leaf spring packets fastened on said channel member and bearing at their ends on said journal members on said axles, and link members extending in the direction of travel and pivotally connected at their ends to said journal members and channel member, respectively.

6. A vehicle truck according to claim 1, in which the means for journaling the rigid chassis assembly on the axles includes supporting connecting means between said journal members and said rigid chassis assembly, and a transverse link pivotally connected at its ends to one of said journal members and to said chassis, respectively, to prevent lateral movement between said chassis and said journal members.

7. A vehicle truck according to claim 1, in which the means for journaling the rigid chassis assembly on the axles comprises said journal members on said axles, and means including resilient rubber blocks forming a supporting connection between said journal members and said chassis.

8. A vehicle truck according to claim 1, gear housings enclosing the respective geared driving connections between said motor shafts and wheel axles and rigidly connected to the respective journal members and a rigid member extending between and connected to the gear casing and journal member at the opposite end of each axle, respectively.

9. In a vehicle truck according to claim 1, a gear housing enclosing the respective geared driving connections between said motor shafts and said axles and rigidly connected to the respective journal members, and a pivoted suspension link connecting said gear housing with said chassis assembly.

10. In a truck for a rail vehicle frame having a center pin, spaced wheeled axles, a transverse channel member disposed intermediate said wheeled axles and having upstanding side walls extending parallel to said axles, a driving motor rigidly secured to the outside of each of said side walls to form a rigid chassis assembly with the shafts of said motors disposed parallel to said axles, means including journal members on said axles for journaling the rigid chassis assembly on said axles, geared driving connections between the respective motor shafts and wheel axles, a swing bolster housed by said channel member between the side walls thereof, means for resiliently supporting said bolster in said channel member, two power transmitting thrust links arranged perpendicularly to each other, one of said links connecting the center pin of the vehicle body to the chassis formed by said transverse channel member and motors and the other link connecting the center pin to the swing bolster.

11. In a truck for a rail vehicle frame having a center pin, spaced wheeled axles, a transverse channel member disposed intermediate said wheeled axles and having upstanding side walls extending parallel to said axles, a driving motor rigidly secured to the outside of each of said side walls to form a rigid chassis assembly with the shafts of said motors disposed parallel to said axles, means including journal members on said axles for journaling the rigid chassis assembly on said axles, geared driving connections between the respective motor shafts and wheel axles, a swing bolster housed by said channel member between the side walls thereof, means for resiliently supporting said bolster in said channel member, two power transmitting link members arranged perpendicularly to each other, one of said link members connecting the center pin to the chassis formed by said transverse channel member and motors and the other link member connecting the center pin to the swing bolster, and roller members journaled on said swing bolster.

on each side of the center point thereof for supporting engagement with the vehicle frame.

12. A vehicle truck comprising spaced wheeled axles, a transverse channel member disposed intermediate said wheeled axles and having upstanding side walls extending parallel to said axles, a driving motor rigidly secured to the outside of each of said side walls to form a rigid chassis assembly with the shafts of said motors disposed parallel to said axles, means including journal members on said axles for journalling the rigid chassis assembly on said axles, geared driv-

ing connections between the respective motor shafts and wheel axles, a swing bolster housed by said channel member between the side walls thereof, and means for resiliently supporting said bolster in said channel member comprising a leaf spring member on each side of said swing bolster, said spring members being fastened centrally thereof to the channel member and linked at their ends to the respective ends of said swing bolster.

FRANZ PRANTL.
